Pa., assignors to Phoenix Glass Company,
Monaca, Pa., a corporation of West Virginia

Application August 28, 1940, Serial No. 354,526

4 Claims. (Cl. 240—78)

Our invention relates to lighting fixtures and more particularly to light transmission shields of glass or other transparent or semi-transparent material for enclosing or shielding fluorescent lamp tubes or other types of lamps.

Briefly stated, our invention comprises a shield of glass or the like, together with means for supporting it in position beneath or in front of a lamp tube or tubes, in an improved manner.

One object of our invention is to provide a shield and a holder therefor of such form that the holders and shield can readily be applied to various standard forms of lamp structures, and whereby the shield can easily be applied and removed from the holder without the necessity of operating any fastening elements such as screws.

Another object of our invention is to provide an arrangement whereby stock lengths of shield elements can be employed in connection with lamp tubes of various lengths, rendering unnecessary the forming of shield elements of certain particular lengths to fit over each of various lengths of lamp tubes.

Some of the forms which our invention may take are shown in the accompanying drawing wherein Figures 1, 2 and 3 are perspective views showing the shield in position in its holder and indicating the manner in which it is manipulated to disengage it from the holder; Fig. 4 is a side view of an illuminating unit, partially in section and with the shield elements spread apart slightly at their ends; Fig. 5 is a bottom plan view of one of the shielding elements on an enlarged scale; Fig. 6 is a view partially in end elevation and partially in section of a modified form of shielding element, and Fig. 7 is a side view of a shielding unit embodying elements of the form shown in Fig. 6.

The shield is shown as positioned around a lighting tube 8 which has connection with terminals 8a that are carried by a bracket 9 and suitably wired. In some cases a number of tubes 8 are comprised within a single lamp structure. The bracket 9 is carried by a combined cover plate and shield holder 10 that has flanges or ledges 11 and 12 disposed at opposite sides of the lamp 8. The shield comprises elements 13 that have flanges 14 formed on their longitudinal edges in position to rest upon the ledges 11 and 12, to thereby afford support for the elements 13. Ribs or shoulders 14a are formed on the undersides of the flanges 14 and normally have abutting engagement with the innermost edges of the ledges 11 and 12, as shown in Fig. 1, in order to

prevent accidental lateral shifting of the shield elements.

When it is desired to remove a shielding element, it is lifted at one edge, or both edges, as shown in Fig. 2, whereupon it can be slid laterally to permit one edge thereof to be lowered from the holder 10, as shown in Fig. 3, thereby permitting the element to be laterally shifted clear of the holder. Where the ends of the elements overlap, as hereinafter described, they will be shifted longitudinally a short distance to clear them of one another and permit removal of each element as indicated in Figs. 2 and 3.

Each element has on one end a rib 15 that is recessed on its inner periphery for receiving a flange 16 of relatively small radius, that extends from a rib 17 on an end of an adjacent element. This overlapping of the adjacent ends of the shield elements permits the rib 15 of one element 18 to be brought into abutting engagement with the rib 17 of an adjacent element, when moved together from their expanded positions shown in Fig. 4. The flange 16 serves to obstruct rays of light that would otherwise freely pass between adjacent ends of the shield elements.

The holder 10 carries end plates 18 and 19 that cover the extreme ends of the shield, and one or both of these end plates is provided with a spring finger 20 that when expanded yieldably holds the shield elements 13 in snug end-to-end engagement with one another. When it is desired to remove one of the shield elements 13, it is shifted lengthwise in a direction to cause compression of the spring 20 and to free its flange 16 from engagement with an adjacent shield element, whereupon it can be tilted and removed from the holder 10 independently of the other shield elements.

In Fig. 6 I show a shield element 21 of somewhat different form than that of Figs. 1 to 5, in that while it has flanges 22 that are adapted to rest upon the ledges 11 and 12, at least one wall of the element immediately beneath one of the flanges 22 and 23 is thickened as indicated at 24, so that when that side of the shield element is raised to bring the shoulder 24 above the ledge 11, the element may be slid sidewise to allow its flange 23 to be moved downwardly past the ledge 12. Ordinarily, a shoulder 24 will be provided also beneath the flange 23. The ends of the elements 21 may be recessed and flanged, as at 15 and 16 in Fig. 5.

We claim as our invention:

1. A shielding device for lamps, comprising horizontally-disposed shield-holding ledges and

means for supporting them at opposite sides of a lamp, shield elements of generally channel form positioned in longitudinal alignment and each arranged to be positioned outwardly of the lamp, marginal flanges on opposite sides of the shield elements and fitting behind said ledges, the elements being slideable longitudinally of the ledges, stop shoulders on the sides of each shield element at the bases of the flanges, positioned to engage the adjacent edges of the ledges, each shield element being of reduced width at points outwardly from the shoulders, whereby when one side of the shield element is pushed inwardly to disengage its shoulder from the adjacent ledge, the shield element can be freely moved sidewise to cause the flange at its other side to be moved clear of its associated ledge and permit that side of the shield element to be swung outwardly from said ledge, and a spring positioned to exert endwise thrust on the shield elements, to yieldably maintain them in end-to-end relation.

2. A shielding device for lamps, comprising horizontally-disposed shield-holding ledges and means for supporting them at opposite sides of a lamp, shield elements of generally channel form positioned in longitudinal alignment and each arranged to be positioned outwardly of the lamp, marginal flanges on opposite sides of the shield elements and fitting behind said ledges, and stop shoulders on the sides of each shield element at the bases of the flanges, positioned to engage the adjacent edges of the ledges, each shield element being of reduced width at points outwardly from the shoulders, whereby when one side of the shield element is pushed inwardly to disengage its shoulder from the adjacent ledge, the shield element can be freely moved sidewise to cause the flange at its other side to be moved outwardly clear of its associated ledge and permit that side of the shield element to be swung outwardly from said ledge, adjacent ends of the shield elements fitting in telescopic relation with one another.

3. A shielding device for lamps, comprising horizontally-disposed shield-holding ledges and means for supporting them at opposite sides of a lamp, shield elements of generally channel

form positioned in longitudinal alignment and each arranged to be positioned outwardly of the lamp, marginal flanges on opposite sides of each shield element and fitting behind said ledges, 5 stop shoulders on the sides of each shield element at the bases of its flanges, positioned to engage the adjacent edges of the ledges, each shield element being of reduced width at points outwardly from the shoulders, whereby when one side of the shield element is pushed inwardly to disengage its shoulder from the adjacent ledge, the shield element can be freely moved sidewise to cause the flange at its other side to be moved clear of its associated ledge and permit that side of the shield element to be swung outwardly from said ledge, adjacent ends of the shield elements fitting in telescopic relation with one another, and spring means carried by the ledge-supporting means, for yieldably maintaining said relation.

4. A shielding device for lamps, comprising horizontally-disposed shield-holding ledges and means for supporting them at opposite sides of a lamp, shield elements of generally channel 25 form positioned in longitudinal alignment and each arranged to be positioned outwardly of the lamp, marginal flanges on opposite sides of the shield elements and fitting behind said ledges, the elements being slideable longitudinally of the ledges, a stop shoulder on one side of each shield 30 element at the base of the adjacent flange and positioned to engage the edge of the adjacent ledge, each shield element being of reduced width at points outwardly from its marginal flanges 35 and the said shoulder, whereby when one side of the shield element is pushed inwardly to disengage its shoulder from the adjacent ledge, the shield element can be freely moved sidewise to cause the flange at its other side to be moved clear of its associated ledge and permit that side of the shield element to be swung outwardly from said ledge, and a spring positioned to exert endwise thrust on the shield elements, to yieldably maintain them in end-to-end relation.
